United States Patent Office

Des. 192,197
Patented Feb. 6, 1962

192,197

HOUSEBOAT

Ormond L. Luger, 9612 Oakland Ave., and Rennold J. Luger, 4505 Belvidere Lane, both of Minneapolis, Minn.

Filed Dec. 22, 1960, Ser. No. 63,298

Term of patent 14 years

(Cl. D71—1)

FIG. 1

FIG. 2

FIG. 3

FIG. 1 is a front perspective view of a houseboat illustrating our new design;

FIG. 2 is a side elevational view thereof; and

FIG. 3 is a rear elevational view thereof.

The dominant features of our design reside in the portions thereof shown in full lines.

We claim:

The ornamental design for a houseboat, as shown and described.
